UNITED STATES PATENT OFFICE.

WILLIAM B. KIEHL, OF PITTSBURGH, PENNSYLVANIA.

AWNNG-PULLEY.

1,241,992.

Specification of Letters Patent.

Patented Oct. 2, 1917.

Application filed January 7, 1916. Serial No. 70,837.

To all whom it may concern:

Be it known that I, WILLIAM B. KIEHL, a citizen of the United States, and a resident of Pittsburgh, in the county of Allegheny and State of Pennsylvania, have invented a new and useful Improvement in Awning-Pulleys; and I do hereby declare the following to be a full, clear, and exact description thereof.

10 My invention pertains to pulleys, and relates especially to pulleys for use in connection with awnings and the like. Pulleys of the ordinary construction, when used in connection with awnings or other devices where 15 fabric is liable to come into contact with the pulley, are open to the objection that the fabric of the awning or the like is liable to be drawn into the throat of the pulley, either above or below the pulley-wheel, and thereby to become damaged. In this way the 20 awning or the like becomes damaged in spots, and thus worn out before its time. It is one object of the present invention to obviate the disadvantage referred to above by 25 providing a pulley in which means are provided for effectually preventing the fabric from being drawn into any part of the pulley. It is another object of the invention to provide a pulley which, while thus 30 preventing the fabric from being drawn thereinto, will be of a simple construction and cheap of manufacture. And other and further objects of the invention will appear from the following specification, taken in 35 connection with the claims annexed thereto.

One form of awning pulley constructed in accordance with my invention is shown in the accompanying drawings and described, by way of example, in the following specification. It is to be understood, however, 40 that the invention may be embodied in other forms, and that changes may be made in the form described and shown, without exceeding the scope thereof, as defined in the appended claims.

In the drawing:

Figure 1 shows a form of awning to which my invention may be advantageously applied;

50 Fig. 2 is a section on the line 2—2 of Fig. 1;

Fig. 3 is a side view of an awning-pulley constructed in accordance with my invention;

Fig. 4 is a perspective view of the awning 55 pulley, with the parts separated; and

Fig. 5 is a section on the line 5—5 of Fig. 3.

Like reference characters refer to like parts throughout the following specification and the several figures of the accompanying drawing.

The awning shown in Figs. 1 and 2 comprises an awning top 10 secured at its upper edge 11 to the window-front and having a 65 rod along its lower edge 12. The top 10 is provided with triangular end pieces 13 along the lower edges of which extend bars 14 hinged to the window front. As a usual means of raising and lowering the awning 70 ropes *a*, *b* and *c* are employed. The rope *a* passes over a pulley *a'* and thence to the lower edge 12 of the awning-top. The rope *b* passes over a pulley *b'* and thence over a 75 pulley *b''* to the lower edge 12 of the awning top. The rope *c* passes over a pulley *c'* and thence over a pulley *c''* to the lower edge 12 of the awning top. It will readily be seen that by pulling upon the ropes *a*, *b* and *c* the awning is raised, while by releasing said ropes the awning is permitted to fall into operative position. All of the ropes are located within the awning-top, the 80 pulleys referred to being situated just within the upper edge 11 thereof. In the case 85 of an awning such as has just been described, the fabric of the awning is liable to enter the throats of ordinary pulleys, and thereby to become destroyed in spots. To obviate this, one form of my improved pulley is 90 constructed as follows:

Referring to Figs. 3-5, the pulley described therein comprises a back plate 15, usually of oval shape, provided with a flange 16, which extends around the front edge 95 thereof. The flange 16 is formed with a tubular extension 17 disposed so as to extend tangentially to the periphery of a pulley wheel 18 one end of the spindle of which is mounted to rotate in the back plate 15. 100 The flange 16 is formed, at the top of the back-plate, with a recess 19 for receiving the shank 20 of a swivel 21. Coöoperating with the back-plate 15 is a front-plate 21 which is formed with a hole for receiving 105 the spindle of the pulley-wheel 18, and is adapted to be secured to the back-plate by means of rivets 22, the front plate being

spaced from the back-plate by abutting against the flange 16. The front plate is formed with an ear 23 which enters the recess 19 and confines the swivel 21 in its proper position. When the parts of the pulley are assembled, the rear thereof is open and the front thereof, above and below the tubular extension 17, is closed by the flange 16.

- 10 It will be seen that the construction of pulley described above effectually prevents any of the awning-fabric from being drawn into the throat of the pulley, either above or below the pulley wheel. The tubular extension 17 will usually prevent the fabric from being brought up close to the pulley; and, should the fabric come into contact with the pulley, the portions of the flange 16 above and below the tubular extension prevent the fabric from entering the throat of the pulley at either part. While obtaining the above advantage, the pulley is of simple construction and may be manufactured at an exceedingly low cost.
- 15 20 25 Having thus fully described my invention, what I claim as new, and desire to secure by Letters Patent, is:

1. An awning-pulley comprising a back plate having a laterally extending flange around the front half only of the periphery thereof, said flange having a recess adjacent the top thereof and being formed inter-

mediate its ends with an elongated tubular extension, a front plate secured to said back plate and abutting against said flange, said front plate having a portion extending into said recess, a swivel mounted in said recess, and a pulley-wheel mounted to rotate between said front and back plates.

2. An awning pulley comprising a unitary metallic back-member including a plate-portion having a flange-portion extending partially therearound and terminating at points adjacent the top and bottom, and having an elongated tube extending angularly outward from said flange-portion intermediate the ends of the latter, said flange-portion having a transverse slot formed therein near the top, a front-member consisting of a flat plate having a lug adapted to enter said slot when said plate is superposed on the flange of said back-member, means for securing said front-member to said back-member, a pulley rotatably mounted between said members, and a supporting swivel disposed in said slot and retained in position by said flange and said lug, for the purposes set forth.

In testimony whereof, I, the said WILLIAM B. KIEHL, have hereunto set my hand.

WILLIAM B. KIEHL.
